[57] CLAIM

The ornamental design for a motor housing with integral guard apron for a grass cutter, as shown and described.

DESCRIPTION

FIG. 1 is an elevational view of one side of the motor housing with integral guard apron for a grass cutter showing my design, the other side being mirror-identical thereto;

FIG. 2 is a front elevation thereof;

FIG. 3 is a rear elevation thereof; and

FIG. 4 is a top elevation thereof.

The bottom of the motor housing with integral apron, is unornamented.

FIG. 1

FIG. 2

FIG. 3

FIG. 4
